F. SAMUEL

WINDOW SCAFFOLD

Filed Dec. 17. 1923

Inventor

Frank, Samuel.

Attorney

UNITED STATES PATENT OFFICE.

FRANK SAMUEL, OF DETROIT, MICHIGAN.

WINDOW SCAFFOLD.

Application filed December 17, 1923. Serial No. 681,268.

To all whom it may concern:

Be it known that I, FRANK SAMUEL, a former citizen of the Republic of Poland, who has declared his intention of becoming 5 a citizen of the United States, and who is residing at Detroit, in the county of Wayne and State of Michigan, has invented a new and useful Improvement in a Window Scaffold, of which the following is a specification.

10 My invention relates to a new and useful improvement in a window scaffold and has for its object the provision of a window scaffold which will be simple in structure, 15 economical of manufacture and highly efficient in use.

Another object of the invention is the provision of a scaffold adapted for attachment 20 to a building at the exterior of a window and provided with means adapted to engage the sloping sill of the window and retaining the scaffold in horizontal position.

Another object of the invention is the provision of a window scaffold having a platform and super-structure adapted for folding 25 into compact position for carrying the same.

Another object of the invention is the provision of a window scaffold having means 30 adapted for engagement with the sash of the window for retaining the scaffold in mounted position on the window.

Other objects will appear hereinafter.

The invention consists in the combination 35 and arrangements of parts hereinafter described and claimed.

The invention will be best understood by a reference to the accompanying drawings which form a part of this specification and 40 in which,

Fig. 1 is a central vertical sectional view of the invention, showing parts in elevation,

Fig. 2 is a front elevational view of the 45 invention,

Fig. 3 is a sectional view taken substantially on line 3—3 of Fig. 1.

The invention is adapted for use in washing windows and the like and is designed 50 to be mounted on the window sill so that the one washing the windows may have a suitable support at the exterior of the window, permitting free use of both the hands and arms.

55 In the preferred form of structure, the invention comprises a supporting member,

or platform 8, projecting upwardly from which, at two corners, are rails 9 to the upper ends of which are hingedly connected, as at 10, extensions 11 of these rails. The 60 rail 9 is hingedly connected to a cross bar 12 mounted on the upper surface of the platform 8 at its extremities. The rails 11 are connected by cross member 13. The structure is such that the rails 11 may be folded 65 upon the rails 9 so that the member 13 will lie in engagement with a cross member 14, mounted on the upper surface of the platform 8, which serves as an abutment for the rails 9 when raised to upright position, as 70 shown in Fig. 1. The rails 9 may likewise be folded upon the platform. Mounted at the other two corners of the platform are upright rails 15, which are hingedly connected to the member 12 so as to fold inwardly upon the platform 8. These members when raised to upright position are prevented from folding inwardly by means of a pivoted arm 16 which is mounted thereon and provided with a notch 17 adjacent 75 its free end for engaging a stud 18, mounted on the edge of the platform 8. Hingedly connected to the members 15, intermediate their ends are cross arms 19, each of which is provided with a downwardly projecting 80 tongue 20 which engages in a U-shaped eyelet 21, mounted on the member 9. In this way, the member 9 is prevented from folding 85 while in use. Hingedly mounted upon the member 15, adjacent its upper end is a cross arm 22, which is provided, at its free 90 end, with a downwardly projecting tongue 23, adapted to engage in a U-shaped eyelet 24 mounted upon the member 11. In this way section 11 is prevented from folding 95 when in use. It is also to be noted that the cross arms 22 engage the members 11, intermediate their length so that the rail 13 projects above the cross arms 22. Mounted upon the under surface of the platform 8 is a strip of metal 25 which is angularly turned at 26 to engage the forward end of the platform 8. A portion 27 extends from this angularly turned portion and carries an angularly turned portion 28 terminating 100 in a portion 29 which is fastened to one end 30 by suitable bolts of an L-shaped member projected through the other leg 31 of which is a suitable screw 32 having a head 33 provided with wings. Mounted upon the under 105 surface of the platform 8, over the strip 25 is a strip 34, made from some resilient metal,

said strip having an angularly turned portion 35, projecting forwardly from which is a portion 36 having a doubled over portion 37 which terminates in an elongated portion 38.

In mounting the device for use the portion 35 is placed in engagement with the sloping sill 39 of the window casing 7. The portion 27 lies in engagement with the upper surface of the window sill and the set screw 32 is threaded into engagement with the under surface of the window sill. When in this position the window sash 40 may be lowered into engagement with the portions 28 and 27, as shown in Fig. 1. In this way the device is locked upon the window casing by the window, itself, as well as by the set screw. The formation of the metal supports which are attached to the under surface of the platform 8 and which engage the window sill presents to the platform a certain spring effect owing to the doubled over portion 37 of the strip. In this way, a moving about of the operator on the platform will not transmit violent jars to the window sash 40 or the set screw 32, the jars being absorbed by the spring support. As shown in Fig. 2, the L-shaped member may be adjusted on the portion 29 by providing a plurality of openings in the portion 29, through which the bolts may be projected. In this way, the device may be adjusted for use on window sills of varying widths.

While I have illustrated and described the preferred form of structure, I do not wish to limit myself to the precise form of structure shown but desire to avail myself of such variations and modifications as come within the scope of the appended claims.

Having thus described my invention what I claim as new and desire to secure by Letters Patent is:

1. A window scaffold comprising a platform; rails hingedly mounted on said platform and projected upwardly therefrom; adapted to fold inwardly upon said platform; extensions, hingedly connected to said rails and projecting upwardly therefrom, adapted to fold upon said rails; additional rails hingedly connected to said platform,

projecting upwardly therefrom and adapted to fold thereon; and hingedly connected arms mounted on said additional rails for engaging said first mentioned rails and extensions for retaining the same in rigid condition.

2. A window scaffold comprising a platform; rails connected to and projecting upwardly therefrom and adapted for folding thereon; additional rails mounted on said platform and projecting upwardly therefrom and adapted for folding thereon; U-shaped clips mounted on said first mentioned rails, arms hingedly connected on said second mentioned rails; tongues mounted on said arms for engaging in said U-shaped clips for retaining said rails in operative position.

3. A window scaffold comprising a platform; a resilient supporting member mounted on said platform having an angularly turned portion adapted to engage the inclined surface of a window sill with which used; a supporting arm for said platform projecting therefrom and provided with an angularly turned portion adapted for engaging the sash of a window with which used; and adjustable means for securing said supporting arm to said window sill.

4. A window scaffold comprising a platform; rails hingedly connected to and projecting upwardly therefrom and adapted for folding thereon; extensions on said rails hingedly connected thereto and projecting upwardly therefrom and adapted for folding thereon; additional rails hingedly connected to and projecting upwardly from said platform and adapted for folding thereon transversely of the direction for folding of said first mentioned rails; and arms on said additional rails for retaining said first mentioned rails and extensions thereof in operative position; and means pivotally mounted on said additional rails for engaging said platform for preventing the folding of said additional rails on said platform.

In testimony whereof I have signed the foregoing specification.

FRANK SAMUEL.
